UNITED STATES PATENT OFFICE

2,669,059

BUBBLE BLOWING MACHINE

Oxford Douglas McNeill, Forest Hill, Ontario, Canada, assignor to Colgate-Palmolive Company, Jersey City, N. J., a corporation of Delaware.

Application June 1, 1950, Serial No. 165,444

4 Claims. (Ch. 46—8)

1

This invention is for improvements in or relating to bubble blowing devices which are operable automatically to form bubbles continuously from a film-forming bubble liquid.

More particularly, the invention relates to devices of the known type in which a plurality of apertures are moved in succession into contact with a film-forming bubble liquid to entrain bubble-forming films across the apertures and thence moved in succession to an air-delivery station where air is blown across the apertures to create the bubbles.

An object of the invention is to provide a compact device of the type described which is particularly suitable for transportable displays, i. e. is capable of satisfactory operation when mounted for movement as a whole (for example, upon a truck carrying advertising intelligence), under which conditions movement of the surrounding air with respect to the device may adversely affect efficient bubble formation.

According to one aspect of the invention a bubble blower comprises a tank for containing a film-forming bubble liquid, an air-delivery station exterior to the tank, a bubble-film entraining structure including a plurality of film-forming apertures disposed about said structure in non-coplanar relationship with each other, and means for moving said structure to advance the said apertures each along a path which passes below a liquid level in the tank and to the vicinity of the air-delivery station.

In a prior device of the type described, film-forming apertures have been arranged in vertical co-planar relationship; such a co-planar arrangement of the film-forming apertures, however, sometimes gives rise to difficulties in the satisfactory production of bubbles when the device is exposed to cross-currents of air as, for example, when transported by truck. In contradistinction to the prior device, it is found that the non-coplanar arrangement of the film-forming apertures in accordance with the invention, shows little, or relatively little, tendency for movement of the surrounding air to disturb the bubble formation.

The invention includes an arrangement in which the film-forming apertures are so orientated as to lie on a cylindrical (preferably, right-cylindrical) surface. Preferably, the film-forming apertures are contained by one or more rotors being disposed about the axis of rotation thereof in non-coplanar relationship with one another, means being provided to move the rotor or rotors to advance the apertures in the path which passes

2

below the liquid level in the tank to the vicinity of the air delivery station.

Further features of the invention will appear from the following description describing a preferred embodiment of the invention, by way of example, with reference to the accompanying drawings, in which:

Figure 1 is a top plan view of the bubble-blowing device with part broken away to show the internal structure;

Figure 2 is a front elevation of the device;

Figure 3 is a side elevation, and

Figure 4 is a view similar to that of Figure 1, of an alternative embodiment of the invention.

Referring to the drawings:

The device shown in Figures 1, 2 and 3 includes a fluid tank 11, for containing a bubble forming liquid, having a removable cover 12, the tank and its cover being preferably made of stainless steel. At its rear, the tank 11 has a wall 13 which carries an integral vertical extension 13a at the rear of which a box-like housing 14 is secured above the tank by bolts 15 passing through peripheral flanges at vertical margins of a front opening into the housing. The housing 14 is preferably made of aluminum and has an open bottom.

The wall 13 and its vertical extension constitute a supporting panel for the operative parts of the device, as follows:

A plain bearing 17 extends through a centrally disposed opening in the panel 13, 13a projecting over the tank 11 and is bolted in position through an integral flange. A horizontal shaft 18 is journaled for rotation within the bearing 17, a hub 19 being fixed to one end of said shaft where it overlies the tank 11 and a fibre-faced gear wheel 20 being secured to the other end of the shaft behind the panel 13, 13a. Six radial spokes 21 project symmetrically from the hub 19 and support a right-cylindrical band 22 formed with a plurality of apertures 23 which are spaced equidistantly completely around the band as shown. As will be seen more particularly from Figures 1 and 3, the spokes 21 are fixed to the band 22 close to the forward edge thereof. The hub 19, spokes 21 and band 22 constitute a bubble-film entraining structure, or rotor, which dips below the liquid level in the tank 11, the high-level of which should preferably not exceed the level indicated by the line 24 in Figure 3. It has been found that successful bubble formation can be achieved with circular apertures 23 having a diameter of 0.62 inch, spaced on 0.87 inch centres, with a rotor diameter of 5 inches. The

band 22 is conveniently made of 0.01 inch thick brass strip, the spokes 21 and hub 19 also being made of brass. The cover 12 has a rectangular cut-away opening 25 to accommodate the rotor structure while covering substantially the whole 5 of the remainder of the tank.

The rotor is driven by a motor 26, which may conveniently consist of a six-volt car-heater motor, which is mounted upon supporting columns from the rear of the panel 13, 13a. Drive from 10 the motor 26 is transmitted through an intermediate pinion 27 on the motor shaft to a gear wheel 28 integral with a second pinion 29 which in turn drives the gear wheel 20. The gear 28 and pinion 29 are supported for rotation in a bearing member secured to the panel 13, 13a. The gear ratio and motor speed is such that the final 15 speed of the rotor structure is approximately 60 R. P. M. which has been found in practice to be an effective operating speed in the present arrangement.

An elliptical aperture is provided in the panel 13a, through which projects a circular air-duct 30 forming the delivery nozzle of a motor and fan assembly 31 supported by a bracket from the rear of the panel 13a. The duct 30 is inclined to the panel at an angle of approximately 45° in both the outward and downward directions, as shown in Figures 1 and 3, and terminates forwardly in an internal sleeve 32 which may be adjusted longitudinally of the duct 30 and secured in adjusted position by a set screw 32'. The motor and fan assembly 31 serves to deliver air through the duct 30 and sleeve 32 to a region close to the rotor band 22 which may be adjusted by the setting of the sleeve 32. The forward end of the sleeve 32 thus constitutes an air-delivery station. Owing to the inclined disposition of the duct 30 and internal sleeve, air is delivered through the panel 13a slantwise of the axis of the rotor structure so as to pass upwardly and outwardly through the apertures 23. The speed of the motor and fan assembly 31 is regulated so that the quantity and velocity of the air delivered through the duct 30 produces large quantities of bubbles at the given rotor speed while not being so violent as to disrupt the bubble films prior to bubble formation.

In the operation of the device the rotor assembly rotates in a clockwise direction (as viewed in Figure 2), the apertures 23 each moving along a path which passes below the liquid level in the tank 11 and thence to the vicinity of the forward end of the air-delivery duct 30. An anti-clockwise rotation of the rotor assembly may, however, be employed. As each aperture leaves the bubble liquid in the tank 11, it entrains with it a bubble film which is then blown into one or more bubbles in its further movement past the end of the duct 30 and a continuous production of bubbles ensues.

The apertures 23, being formed in the surface of the cylindrical band 22, are arranged in non-coplanar relationship with one another. This arrangement, as explained previously minimizes the effect of movement of the surrounding air in disturbing, and possibly breaking, the bubble films prior to their presentation at the air-delivery aperture.

To minimize oscillation of the bubble-forming liquid in the tank 11 when the device is arranged as a transportable display, the tank 11 is provided with a forward vertical baffle 33 which extends the length of the tank from an upper edge lying below and closely adjacent to the lid 12,

to a lower edge which is clear of the bottom of the tank as shown in Figure 2. The baffle 33 is secured through flanges 34 and 35, as by soldering, to opposite end walls of the tank. Further vertical baffles 36, 37 extend inwardly from opposite end walls of the tank rearwardly of the rotor 22 and terminate short of the bearing 17. Baffles 36 and 37 have upper edges lying closely below the lid 12 and terminate in lower flanges 38 and 39 respectively, which are secured to the bottom of the tank. Side flanges 40, 41 also secure the outer ends of the baffles 38, 39 to the end walls of the tank 11.

The alternative embodiment of the invention shown in Figure 4 is similar to the construction already described except that two rotor structures are used, each being associated with a separate air duct and motor-fan assembly.

In Figure 4 similar reference numerals are used for parts in that figure which are similar to those parts shown in Figures 1 to 3.

Referring to Figure 4, it will be seen that a second rotor structure is provided comprising an apertured cylindrical band 22a supported similarly to band 22 by spokes projecting symmetrically from a hub 19a. A second air duct 30a having an adjustable sleeve 32a extends rearwardly through the panel 13a from a point close to the rotor band 22 and forms part of a second motor and fan assembly 31a. The operation of the device of Figure 4 is similar to that already described in connection with the first embodiment of the invention, but, in including two rotor structures, is capable of the production of a greater quantity of bubbles in a given time than the first embodiment of the invention.

While the invention has been described, for the purpose of illustration, with reference to specific embodiments employing one or more cylindrical band rotors, it should be understood that various changes in detail may be made, as will be apparent to one skilled in the art, within the scope of the invention.

For example, it is not essential that the rotor assembly be mounted for rotation about a concentric shaft 18 as shown. The hub 19 or hubs 19, 19a could alternatively be disposed in eccentric relationship with respect to the band 22, or bands 22, 22a. Further, the use of one or more cylindrical bands is not essential; they may be replaced, for example, by an equivalent framework comprising arms carrying dipping rings which rings are so disposed that they lie in non-coplanar relationship with each other. While continuous rotational movement of the rotor is preferred, it is also within the ambit of the invention to employ driving means such that the rotor structure oscillates backwards and forwards (by a suitable conventional arrangement of the driving gearing) to bring the film-forming apertures alternately below the liquid level in the tank 11 and to the vicinity of the air-delivery station or stations.

What I claim as my invention is:

1. A bubble blower comprising, a tank for containing a film-forming bubble liquid, a hub means for supporting the hub for rotation within the tank, a hollow thin-walled cylindrical rotor supported from said hub in concentric relationship therewith with a chordal segment of the rotor below a liquid level in the tank, said rotor having a plurality of film-forming apertures in the cylindrical wall thereof, an air-delivery station exterior to the tank, a motor for rotating said hub and rotor to advance said aperture suc-

5

sively beneath the liquid level in the tank, a motor-driven blower to deliver air to said station, and means to direct air from said station slantwise across said rotor from the inside to the outside thereof through said apertures.

2. A bubble blowing machine which comprises a hollow rotatable bubble-film entraining rotor having a cylindrical surface and a plurality of film-forming apertures in and opening through the cylindrical surface, a driven shaft attached to the rotor and coaxial with the cylindrical axis of the latter, a tank adapted to contain a film-forming bubble liquid operatively positioned to enclose a chordal segment of the rotor below a liquid level in the tank, a motor, means operatively connecting the motor to the shaft and to the rotor to advance said apertures continuously in succession along an orbital path which passes beneath the liquid level in the tank, the apertures entraining the liquid in the form of films, means producing a draft of air, and means directing the draft of air through the apertures in said rotor from the inside to the outside thereof in a direction slantwise of the cylindrical axis of the latter to produce bubbles from said films.

3. A bubble blower comprising, a hollow rotor having a cylindrical surface mounted for rotation about an axis, a plurality of film-forming apertures in and opening through the cylindrical surface of the rotor, a tank for containing a film-forming bubble liquid, said tank being operatively positioned to submerge a portion of the cylindrical surface of said rotor and the apertures therein below a liquid level in the tank, an air delivery station adjacent to another portion of the cylindrical surface of said rotor and the

6

apertures therein above said liquid level, motor means moving said rotor along an orbital path which passes below the liquid level in the tank and to the vicinity of the air delivery station, and means directing air from said station slantwise to the axis of rotation of said rotor from the inside to the outside thereof through said apertures for producing bubbles.

4. A bubble blower comprising, a movable 10 bubble-film entraining structure having an axis of rotation and a plurality of film-forming apertures disposed about said structure, said apertures being so oriented as to lie substantially on a right cylindrical surface, a tank for containing 15 a film-forming bubble liquid, said tank being operatively positioned to enclose a portion of said structure and the apertures therein below a liquid level in the tank, an air delivery station adjacent to another portion of said structure and 20 the apertures therein above said liquid level, motor means moving said structure along a path which passes below the liquid level in the tank and to the vicinity of the air delivery station, and means directing air from said station slantwise to the axis of rotation of said structure and 25 through said apertures for producing bubbles.
